COPYHOLDER

Stephen Sattler, Tulsa, Okla.

Application January 23, 1951, Serial No. 207,352

12 Claims. (Cl. 120—32)

1

This invention relates to improvements in a collapsible copy holder of the type for holding copy and advancing the copy a line at a time.

A principal object of my invention is to provide a simplified form of collapsible copy holder arranged with a view toward the utmost efficiency in construction and operation.

A further object of my invention is to provide a copy holder having a novel and efficient positive locking means for automatically locking the copy holder in an operative position.

A still further object of my invention is to provide a novel form of copy holder of the collapsible type, movable vertically into an extended position and having a collapsible line guide member separate from the copy holder, but cooperating therewith, to hold the paper to the copy holder, together with release means for the copy holder also releasing the line guide and extensibly or retractably moving the line guide with the copy holder.

A still further object of my invention is to provide a new and improved copy holder together with a separate line guide cooperating therewith and holding the paper to the copy holder, with individual locking means for the copy holder and line guide, together with release means therefor, releasing the line guide upon release of the copy holder and automatically locking the line guide and copy holder in extended positions.

A further and more detailed object of my invention is to provide an improved collapsible copy holder having a separate line guide extensibly or retractably movable therewith, together with an improved locking means therefor, automatically locking the copy holder in an extended position, together with lever means actuated upon movement of the locking means to an unlocking position, to move into engagement with and release the line guide for collapsible movement, and moving the line guide with the copy holder upon extensible or retractile movement thereof.

A still further object of my invention is to provide a novel form of line guide and cross head for holding paper to the copy holder after the end thereof has passed by the platen of the copy holder.

A still further and more detailed object of my invention is to provide a copy holder having a rotatable platen for feeding the paper with respect to the copy holder a line at a time, together with a cross head having a pressure roller holding the paper in engagement with the platen and formed to hold the bottom of the paper in a readable position after release from the platen.

2

These and other objects of my invention will appear from time to time as the following specification proceeds and with reference to the accompanying drawings wherein:

5 Figure 1 is a front view of a copy holder constructed in accordance with my invention, showing the copy holder in a vertically extended position;

10 Figure 2 is a view in side elevation of the copy holder shown in Figure 1;

Figure 3 is a transverse sectional view taken substantially along line III—III of Figure 1;

15 Figure 4 is an enlarged fragmentary transverse sectional view showing certain details of the latching and unlatching means for the copy holder and line guide;

20 Figure 5 is an enlarged fragmentary transverse sectional view taken substantially along line V—V of Figure 1, showing the copy holder latched in an upwardly extended position;

25 Figure 6 is a view somewhat similar to Figure 5, but showing the copy holder in an unlatched position;

Figure 7 is a fragmentary detailed horizontal 30 sectional view showing the release means for the line guide latching member coming into position to engage and release the line guide latch;

35 Figure 8 is a view somewhat similar to Figure 7 but showing the line guide latching mechanism in an unlatched position in interengagement with the line guide; and

Figure 9 is an enlarged fragmentary transverse sectional view showing certain details of the line guide and cross head with the copy guides on the copy holder in an operative position.

In the drawings:

The embodiment of my invention illustrated is shown as being incorporated in a copy holder of the same general construction as that disclosed in 40 Patents Nos. 2,170,161 and 2,503,355 and application Serial No. 143,699, filed by me on February 11, 1950, and entitled "Collapsible Copy Holder." The copy holder, however, need not be so constructed and I do not wish to be construed as limiting myself to the particular form of copy holder illustrated therein.

As herein shown, the copy holder includes a base 10 having an arm 11 extending from one end thereof. The arm 11 is shown as being in 50 the form of an angle iron in cross section, and may be secured to a desk or table to hold the copy holder upright. The arm 11 also forms a pivotal support for an operating link and lever mechanism indicated generally by reference character 12, for rotating a platen 14 step by step. The platen 14 is journaled in a copy

holder frame 15, mounted on said base for vertical extensible movement with respect thereto. The link and lever mechanism 12 and the mechanism actuated thereby for rotatably moving the platen a line at a time is shown and described in my Patent No. 2,170,161, dated August 22, 1939, and is no part of my present invention, so need not be shown or described in detail herein.

The copy holder frame 15 is shown as being slidably mounted on two upright rods 17-17 suitably secured to the base 10 at their lower ends and extending upwardly therefrom in parallel relation with respect to each other. The upright rods 17-17 each have slidable engagement with two parallel, vertically spaced lugs 19 and 20 extending forwardly from a back 21 of the copy holder frame 15. A rib 23 connects the lugs 20-20 together and serves to stiffen the copy holder frame 15 and also serves as abutment means for spring means for moving and holding the copy holder latching mechanism into an unlatched position, as will hereinafter more clearly appear as this specification proceeds.

The platen 14 is suitably mounted on a shaft 24, for rotation therewith. The shaft 24 is journaled at its ends in side frame members 25-25 of the copy holder frame 15. Said shaft extends outwardly from said side frame members and has knobs 27-27 on its outer ends, to permit turning of the platen by hand independently of the lever operated actuating mechanism therefor, when desired.

A line guide member 29 is spaced forwardly of the copy holder frame 15 and is mounted for extensible or collapsible movement with respect to the base 10 with the copy holder frame 15. The line guide member 29 is herein shown as including a cross head 30 having two spaced hollow rods or sleeves 31-31 depending therefrom, adjacent opposite ends thereof, in parallel spaced relation with respect to each other. The sleeves 31-31 are slidably mounted on parallel spaced rods 33-33 suitably mounted in the base 10 at their lower ends for yieldable movement with respect thereto, and biased to engage a pressure roll 34 with the platen 14. The pressure roll 34 is herein shown as being rotatably mounted on ears 35-35 extending inwardly from the cross head 30, and exerts pressure on the paper to hold the paper to the platen 14 so the paper may be positively advanced a line at a time, upon progressive turning movement of said platen.

Referring now in particular to the novel form of the cross head 30, wherein said cross head maintains a sheet of paper in position so it may easily be read when the paper has been released from the pressure roll 35, the cross head 30 is herein shown as having an inwardly turned upper end portion or lip 40. The lip 40 is herein shown as extending at right angles to the body of the cross head and engages the lower edge of the paper when released from the pressure roller 34 and supported on copy guides 36 and 37 and trained under an intermediate copy guide 38, as may be seen in dotted lines in Figure 9. The lip 40 of the cross head 30 thus projects partially over the pressure roll 34 and holds the lower edge of the paper from moving upwardly into such a position that the material thereon cannot readily be seen. This remedies an objectionable feature of former copy holders in which it is impossible to read notes or insertions at the bottom of the paper without removing the paper from the copy holder and placing it flat on the desk. While the lip 40 is herein shown as being

turned at right angles with respect to the body of the cross head, said lip need not extend at right angles with respect to the body of the cross head, but may extend at various other desired angles or may be of a uniformly curved formation, as long as its lower edge may come into gripping engagement with the lower edge of the paper when released from the platen 24.

The copy guides 37 and 38 are mounted on parallel spaced pivoted arms 41-41, secured to a transverse shaft 43, having the copy guide 36 secured thereto. The shaft 43 is shown as extending beyond the limits of the copy holder frame 15 to guide paper wider than said frame, and a free open space is provided between the line guide member and the platen 14 to permit the insertion of sheets of paper therebetween, wider than the length of the copy holder frame 15.

The copy guide 36 is herein shown as being secured to the transverse shaft 43 for turning movement therewith and is restrained from movement by the legs 44-44 of a U-shaped spring 45. The legs 44-44 engage opposite sides of the copy guide 36 and restrain the arms 41-41 and copy guides 37 and 38 from movement, and yieldably hold said arms and the copy guides carried thereby in the upwardly extended position shown in Figures 3 and 9.

A means is provided to hold the line guide member and pressure roll 34 out of engagement with the platen 14 and to align the paper with the cross head 29. Said means, as shown, includes two spaced arms 46-46 secured to and extending from a rod 47. The rod 47 is journaled adjacent its ends in the side frame members 25-25 of the copy holder frame 15. A torsion spring 49 encircles the rod 47. One end of said spring is secured to the rod 47, and the opposite end thereof engages the top surface of the lug 19 and urges the rod 47 to move in a direction to hold the lever arms 46-46 in a downwardly extended position out of engagement with the sleeves 31-31 of the line guide member 29. When the arms 46-46 are turned outwardly, by grasping with the hand, to the position shown in Figure 3, the line guide 29 and pressure roller 34 are moved away from the copy holder frame 15 and platen 14 in an obvious manner. The strength of the spring 49 is such that the arms 46-46 were retained in the outwardly extending position shown in Figure 3 by the friction between the ends of said arms and the sleeves 31-31, and said arms are only moved in the downwardly extended position shown in Figure 4 by the spring 49, when positively released from the sleeves 31-31 by hand.

It may here be seen that when the arms 46-46 are in the horizontally extended position shown in Figure 3, moving the pressure roll away from the platen 14, said arms not only form a means for readily inserting the paper in the copy holder, but also form an accurate aligning means, bottoming and aligning the sheet of paper being copied.

Referring now to the novel latching and release means of my invention, for latching and releasing the copy holder frame 15 and line guide 29, a detent rod is provided to lock the copy holder frame in an extended position. The detent rod 50 is pivotally mounted in the side frame members 25-25 and is urged by a torsion spring 51 to pivot in a direction to come into engagement with recessed portions 52-52 of the support and guide rods 17-17. The spring 51 encircles the detent rod 50 and is secured thereto at one of its

ends. The other end of said spring engages the rib 23 and urges the detent rod to pivot in a counterclockwise direction. A winged finger grip 53 is shown as being secured to the outer end of said detent rod, for turning said detent rod against said spring into a released position. The detent rod 50, as herein shown, has two recessed portions formed therein in registry with the guide rod 17-17, the inner sides of which are flat, as indicated by reference character 54. The flat 10 inner sides 54-54 of the detent rod are in alignment with the outer periphery of the support and guide rods 17-17 when said flat sides are in a vertical position. Thus, when the detent rod 50 is turned in a position by the finger grip 53 to position the flat sides 54-54 thereof in alignment with the periphery of the support and guide rods 17-17, the copy holder frame 15 may freely move along said rod into a collapsed position. While the rod 50 is shown as having two recessed portions, it should be understood that the entire rod may be flattened along its length, if desired.

As the copy holder frame 15 is extended along the support and guide rods 17-17 and the detent rod 50 comes into registry with the recesses 52-52, the torsion spring 51 will rapidly turn said detent rod to engage the periphery thereof with the recessed portions 52-52 of the support and guide rods 17-17, locking the copy holder frame 15 in the upwardly extended position shown in Figures 2 and 3. A self-operating means has thus been provided to automatically lock the copy holder frame in the desired position of extension with no attention from the operator who may be extending the copy holder.

The means for locking the line guide member 29 in upwardly extended relationship with respect to the base 10, in the proper alignment with respect to the platen 14, includes a separate spring pressed pin 55 slidably mounted in each rod 33, adjacent the upper end thereof. The pins 55-55 are spring urged into engagement with one or the other of a pair of aligned inclined slotted portions 56-56, formed in opposite sides of each sleeve 31. The pins 55-55 may be urged into engagement with the inclined slotted portions 56-56 by means of an elongated spring wire 58, secured to said pin and extending upwardly through a drilled portion of the rod 33 and abutting an edge thereof, and so inclined with respect to said drilled portion of said rod as to continually urge the pin 55 outwardly with respect thereto. Thus, when the line guide member 29 is moved into the upwardly extended position shown in Figures 2 and 3, the pins 55-55 will be urged into registry with the respective slots 56-56 and hold said line guide in an upwardly extended position with the pressure roller 34 in alignment with the platen 14.

The means for releasing the pins 55-55 from the slots 56-56 upon movement of the detent rod 50 to a released position includes two spaced rocking arms 57-57. Each rocking arm 57 is secured to a rod 59 adjacent the inner sides of the lugs 20-20. The rod 59 is journaled at its ends in the side walls 25-25 of the copy holder frame 15 and has a downwardly turned end portion 60 extending along the outer side of the wall 25 inwardly of the finger grip 53. Each rocking arm 57, as herein shown, extends inwardly from the rod 59 toward the back 21 of the frame 15 and downwardly along the back of said frame and has a forwardly extended bifurcated foot 61, the furcations of which are adapted to register with the 70

inclined slots 56-56, on opposite sides of the sleeves 31-31. The inner edges of the furcations of the feet 61-61 are evenly curved to engage the edge of the pin 55 and move said pin inwardly with respect to the rod 33 into position where it may clear the slot 56 as shown in Figure 8, permitting the sleeve 31 to telescopically move with respect to the rod 33. When the feet 61-61 are in position to release the pins 55-55, engagement thereof with the slots 56-56 will positively move line guide member 29 with the copy holder frame 15, upon movement of said copy holder frame.

The downwardly turned end portion 60 of the rod 59 engages a pin 62 secured to and extending inwardly from the winged finger grip 53. A torsion spring 63 encircles the rod 59 and is secured thereto at one of its ends, while the opposite end thereof may have abutting engagement with the copy holder frame 15, as with the rib 23. Said spring urges the downturned end of the rod 59 into engagement with the pin 62 and is strong enough to release the bifurcated feet 61-61 from the slots 56-56, upon movement of the detent rod 50 into engagement with the recessed portions 52-52 of the rods 17-17.

When the copy holder frame 15 is in the uppermost position of adjustment shown in Figures 3, 4 and 5, with the detent rod 50 positively engaging the recessed portions 52-52 of the support and guide rod 17-17, the pins 55-55 will engage the slots 56-56 of the sleeves 31-31, and the copy holder frame 15 and line guide member 29 will be held in aligned upwardly extended relation with respect to each other, with the pressure roller 34 in position to engage the platen 14.

When it is desired to release the copy holder frame 15, the winged finger grip 53 and detent rod 50 may be turned in a direction, which in Figures 4 and 5 is shown as being a counterclockwise direction, until the flat surfaces 54-54 of the detent rod 50 come into registry with the outer periphery of the support and guide rods 17-17, at which time the copy holder frame 15 may slidably move downwardly along the support and guide rod 17-17, the flat portions of the detent rod 50 sliding along the outer side of said support and guide members. Turning of the winged finger grip 53 in the counterclockwise direction just mentioned, will also turn the rocking arms 57-57 in the same direction by engagement of the pin 62 with the downturned end 60 of the rod 59. This will move the lever arms 57-57 and feet 61-61 from the position shown in solid lines in Figure 4 to the dotted position in this figure into registry with the slots 56-56 and in engagement with the pins 55-55, moving said pins to the released positions shown in Figure 8. Downward pressure on the copy holder frame 15 will then slidably move said pin downwardly along the support and guide rods 17-17, and at the same time will telescope the line guide member 29 by engagement of the feet 61-61 with the slots 56-56.

When it is desired to extend the copy holder, upward pressure may be exerted thereon by gripping with the hand and the entire copy holder frame 15 may be moved upwardly along the support and guide rods 17-17 until the detent rod 50 comes into registry with the recessed portions 52-52 of said support and guide rods. At this time the spring 51 will pivot the rod 59 and move the circumferential portion thereof into engagement with the recessed portions 52-52, positively locking the copy holder frame 15 in its elevated position along the support and guide bars 17-17.

At the same time, the torsion spring 63 will cause the downwardly turned end 60 of the rod 59, to follow the pin 62 and move the bifurcated end portions of the feet 61-61 out of engagement with the slots 56-56, allowing the pins 55-55 to come into engagement with said slots and locking the line guide member 29 in the proper relationship with respect to the platen 14.

It should here be understood that the torsion springs 51 and 63 are both relatively strong springs and that the spring 51 snaps the detent rod 50 into engagement with recessed portions 52-52 as soon as said rod comes into registry therewith. The spring 63 is likewise strong enough to aid pivotal movement of the detent rod 50 into engagement with the recesses 52-52 and cause release of the bifurcated portions of the feet 61-61 from the slots 56-56 with a snap action, simultaneous with engagement of the circumferential portion of the detent bar 50 with the recesses 52-52.

It will be understood that modifications and variations may be effected without departing from the spirit and scope of the novel concepts of the present invention.

I claim as my invention:

1. A copy holder comprising a base, a copy holder frame, a plurality of support and guide members supporting and guiding said frame for vertical movement with respect to said base, and releasable means holding said copy holder frame in position on said support and guide members in extended relation with respect to said base including a pivoted detent rod on said frame, spring means urging said detent rod into interengagement with said support and guide members, and manually operated means operable to move said detent rod into a released position with respect to said support and guide members.

2. A copy holder comprising a base, a support and guide member mounted on and extending upwardly from said base, a copy holder frame slidably guided thereon for vertical movement with respect thereto, and detent means releasably holding said copy holder frame in extended relation with respect to said base including a pivoted detent rod mounted on said frame and a cooperating recessed portion formed in said support and guide member, adapted to be engaged by said detent rod, said detent rod having a flattened portion registering with the periphery of said support and guide member and slidably movable therealong, manually operated means moving said flattened portion into registry with the periphery of said support and guide member, and spring means moving the periphery of said detent rod into engagement with said recessed portion.

3. In a collapsible copy holder, a base, a copy holding frame, a plurality of spaced vertically extending guide members mounted on and extending upwardly from said base, a slidable connection between said copy holder frame and guide members, detent means holding said frame in a vertically extended position along said support and guide member, including a rod pivotally mounted on said copy holding frame and having flattened portions slidable along said guide members and holding the detent rod from pivotal movement when in an intermediate position along said support and guide members, said support and guide members having recessed portions adjacent the upper ends thereof adapted to be engaged by the circumferential portion of said rod when in registry therewith, and spring means urging said rod into engagement with said recessed portions.

4. A copy holder comprising a base, a copy holder frame mounted on said base for vertical movement with respect thereto, a line guide member mounted on said base for vertical movement with respect thereto, manually releasable detent means holding said copy holder frame in extended relation with respect to said base, other means holding said line guide member in extended relation with respect to said base, manually operated means for releasing said detent means, and means operated upon movement of said detent means into a released position for releasing said other holding means, said means having interengaging connection with said line guide member, and vertically moving said line guide member upon vertical movement of said copy holder frame.

5. A copy holder comprising a base, a copy holder frame, two spaced support and guide members mounted on and extending upwardly from said base and having slidable engagement with said copy holder frame and supporting said frame in upwardly extended relation with respect to said base, a line guide member mounted on said base for extensible movement with respect thereto and having a cross head extending across said copy holder frame in advance thereof, detent means having interengaging connection with said support and guide members for holding said copy holder frame in extended relation with respect thereto, other means locking said line guide member in extended relation with respect to said base, and release means for said other holding means pivotally mounted on said copy holder frame and moving into interengaging connection with said line guide member upon release of said detent means, and also moving said line guide member with said copy holder frame upon extensible or retractile movement thereof.

6. A copy holder comprising a base, a copy holder frame, mounted for extensible or retractile movement with respect to said base, two spaced support and guide members extending upwardly from said base and having said copy holder frame slidably mounted thereon, a line guide member supported on said base in advance of said copy holder frame for extensible movement with said copy holder frame, two spaced support and guide members supporting said line guide member in extended relation with respect to said base, a detent member on said copy holder frame having interengaging connection with said support and guide members for holding said copy holder frame in vertically extended relation with respect to said base, other locking means positively locking said line guide member in vertically extended relation with respect to said base, release means for said other holding means pivotally mounted on said copy holder frame and including a release arm movable into interengaging connection with said copy holder frame to release said other holding means and engage and move said line guide member upon vertical movement of said copy holder frame.

7. In a copy holder, a base, a plurality of spaced support and guide members mounted on said base and extending upwardly therefrom, a copy holder frame slidably mounted on said support and guide members, an extensible line guide member spaced in advance of said copy holding frame for movement therewith and including a generally horizontal cross head extending across said copy holder frame, two telescopic support members thereon, each having one part secured to said base and extending upwardly therefrom and another part depending from said cross head and

slidably movable along said one part, a pin and slot connection between said telescopic support members, holding said members in extended relation with respect to each other, detent means holding said copy holder frame in extended position, and lever means pivoted on said copy holder frame and operated by said detent means to move into engagement with said slotted portions and move said pins out of engagement therewith and moving said line guide member upon movement of said copy holding frame.

8. In a copy holder, a base, a copy holder frame extensibly mounted with respect to said base, a line guide member mounted on said base for movement with said copy holder frame and including a generally horizontal cross head extending across said frame and two telescopic support members therefor, one part of each of which is secured to said base and extends upwardly therefrom and the other part of which depends from said cross head and is slidably movable along said one part, a pin in one of each of said parts movable transversely thereof, a slot in the other of each of said parts adapted to be engaged by said pin and hold said members in extended relation with respect to each other, lever means pivoted on said copy holder frame and having foot portions movable into engagement with said slots, and moving said pins into released positions with respect to said slots and also moving said cross head with said copy holder frame upon movement thereof.

9. In a copy holder, a base, a copy holder frame extensibly mounted with respect to said base, a line guide member mounted on said base for movement with said copy holder frame and including a generally horizontal cross head extending across said frame and two telescopic support members therefor, one part of each of which is secured to said base and extends upwardly therefrom and the other part of which depends from said cross head and is slidably movable along said one part, a pin in one of each of said parts movable transversely thereof, inclined slots in opposite sides of each of the other of said parts, one of which is adapted to be engaged by one of said pins to hold said members in extended relation, pivoted levers on said copy holder frame and having bifurcated foot portions engageable with said slots and pins and moving said pins into released positions with respect to said slots and also moving said cross head with said copy holder frame upon movement thereof.

10. In a copy holder, a base, a copy holder frame extensibly mounted with respect to said base, a line guide member mounted on said base for movement with said copy holder frame and including a generally horizontal cross head extending across said frame and two telescopic support members therefor, one part of each of which is secured to said base and extends upwardly therefrom and the other part of which depends from said cross head and is slidably movable along said one part, a pin in one of each of said parts movable transversely thereof, inclined slots in opposite sides of each of the other of said parts, one of which is adapted to be engaged by one of said pins to hold said members in extended relation, pivoted levers on said copy holder frame and

having bifurcated foot portions engageable with said slots and pins and moving said pins into released positions with respect to said slots and also moving said cross head with said copy holder frame upon movement thereof, a pivoted detent rod holding said copy holder frame in extended relation, and lever means connected between said detent rod and pivoted levers and effecting movement of said levers into an engaged position upon movement of said detent means into a released position.

11. In a copy holder, a base, a copy holder frame mounted for extensible movement with respect to said base, a line guide member mounted on said base for movement with said copy holder frame and including a generally horizontal cross head and a telescopic support member therefor, one part of which is secured to said base and extends upwardly therefrom and the other part of which is slidably movable along said one part, a pin in one of said parts, a slot in the other of said parts adapted to be engaged by said pin and hold said parts in extended relation with respect to each other, a lever pivoted on said copy holder frame and having a foot portion movable into engagement with said slot, and moving said pin into a released position and also moving said cross head with said copy holder frame by engagement with said slot.

12. A copy holder comprising a base having an upwardly extending support and guide member secured thereto, a copy holder frame slidably mounted on said support and guide member, detent means holding said copy holder frame in an extended position along said support and guide member, spring means engaging said detent means, a line guide member spaced in advance of said copy holder frame, a rod extending upwardly from said base and having said line guide member slidably mounted thereon, releasable locking means having interengagement with said rod and line guide member and locking said line guide member in vertically extending relation with respect to said base along said rod, a release member for releasing said locking means, pivotally mounted on said copy holder frame and connected with said detent means and operated thereby to come into interengaging connection with said line guide member and release said locking means upon movement of said detent member into a released position, and a spring moving said release member out of interengagement with said line guide member, to effect locking of the same, upon movement of said detent means into locking engagement with said support and guide members.
